US0D1021596S

(12) **United States Design Patent** (10) **Patent No.:** **US D1,021,596 S**
(45) **Date of Patent:** **** Apr. 9, 2024**

(54) **GRINDING DISC**

(71) Applicant: **Ningbo Deyan Technology Co., Ltd.,**
Yuyao (CN)

(72) Inventor: **Guobin Xie**, Yuyao (CN)

(**) Term: **15 Years**

(21) Appl. No.: **29/907,211**

(22) Filed: **Jan. 4, 2024**

(51) LOC (14) Cl. **15-09**

(52) U.S. Cl.

USPC **D15/126**; D8/70

(58) **Field of Classification Search**

USPC D15/9, 17, 28-29, 124-134, 135-137,
D15/138-143; D8/8, 23, 16, 52, 60, 66,
D8/70; D10/64, 65; D7/412

CPC B24B 7/10; B24B 7/186; B24B 23/028;
B24D 7/06; B24D 9/08; B24D 9/085

See application file for complete search history.

(57) **CLAIM**

The ornamental design for a grinding disc, as shown and described.

DESCRIPTION

FIG. 1 is a perspective view of a grinding disc showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the grinding disc that form no part of the claimed design.

1 Claim, 8 Drawing Sheets
